FLASHER

Robert S. Perry, Westfield, N. J., assignor, by
mesne assignments, to Perry Flasher Syndicate,
Westfield, N. J.

Application July 29, 1949, Serial No. 107,497

16 Claims. (Cl. 307—132)

1

This invention relates to an automatic switch or "flasher" for periodically making and breaking an electric circuit.

It is often desirable to intermittently operate or "flash" an incandescent lamp at short regular intervals in order to draw attention to the light. This is particularly desirable in certain advertising displays and in warning lights. It is common to provide automobiles with indicator lights to warn the drivers of other automobiles of intention to turn or stop. These lights are preferably blinked or intermittently operated to attract greater attention.

In the form shown, the present invention is applied to a flasher for blinking the turn indicator lights of an automobile. The flasher unit comprises a stack of metallic plates, a portion of one of which forms a moving switch arm that is arranged to be controlled by a hot wire. The switch, which is spring biased to closed position, is connected in shunt of the hot wire; and the hot wire is connected in series with the light that is to be flashed. When the wire is cool it holds the switch open, and the current which then passes is insufficient to light the lamp but sufficient to heat the wire. As the wire heats it lengthens, permitting the switch to close and shunt out the wire. The current that then passes is sufficient to light the lamp, and the lamp remains lighted until the hot wire has cooled sufficiently to open the switch and thereby restore the circuit to its initial condition. This cycle is then repeated again and again, so that the light continues to blink. The flasher shown may be combined with a relay for operating a pilot light to indicate the operation of the lights controlled by the flasher.

A feature of the present invention is that rapid closing and opening of the switch is secured solely by the interrelationship of only two opposing moments, the switch arms always being biased towards closed position. Another feature of the invention is that due to the specific construction and arrangement most of the factors controlling the duration of the "on" and "off" periods may be very closely controlled, final adjustment being made during assembly solely by the tensioning of the hot wire. The specific construction permits a relatively large amount of tolerance in this adjustment without adversely affecting operation of the flasher.

An object of the present invention is to provide an improved flasher that is durable, sufficiently shockproof, easily assembled and adjusted, and that will retain its adjustment indefinitely.

2

Another object of the invention is to provide a new and improved method of periodically interrupting an electric circuit.

Another object is to provide an improved flasher and relay combined in a single, unitary structure that lends itself to quick and easy assembly.

Another object is to generally improve flashers of the type described.

10 Further objects, and objects relating to details and economies of manufacture, assembly and use, will more definitely appear from the detailed description to follow.

My invention is clearly defined in the appended claims. Where parts are, for clarity and convenience, referred to on the basis of their oriented position shown in the accompanying drawing, no limitation as to positioning of the entire structure is to be implied, since it will be understood that the entire structure may be inverted or that it may be used in any inclined position. Also in both the description and the claims, parts at times may be identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawing forming part of this specification, in which:

Figure 1 is a schematic diagram showing the flasher of the present invention applied to the control of a single lamp.

35 Figure 2 is a wiring diagram of the combined flasher and relay as applied to a turn signalling system of an automobile.

Figure 3 is an exploded isometric view of the combined flasher and relay.

Figure 4 is a top plan view of the plate of the flasher that provides the switch arm and biasing spring.

Figure 5 is a vertical section taken generally on the line 5—5 of Figure 4.

45 Figure 6 is an enlarged, fragmentary, detailed section, showing a knife-edge connection that is interposed between the biasing spring and the switch arm.

Figure 1 discloses the essential principle of 50 operation of the flasher as applied by way of example to a simple circuit. Flow of current is controlled by a switch arm 11 that is pivoted between its ends at pivot point 12 and is capable of oscillating between "on" and "off" positions. A spring 14, which may be of the flat, arched type,

is pivotally mounted at a pivot point 15. This spring engages against an end of the switch arm 11, pressing lengthwise of the arm, the portion of the arm between the pivot 12 and the spring being rigid. A substantially frictionless knife-edge connection 16 (see also Fig. 6) between the arm and spring retains the spring in engagement with the switch arm, the arm and spring forming essentially a toggle. However, the knife-edge connection 16 always remains on the same side of the neutral axis through the pivot points 12 and 15, the abutment 17 serving to prevent the knife-edge connection 16 from crossing this axis. Thus, the spring 14 continuously biases the switch arm 11 laterally in the same direction, i. e. toward closed position. The spring 14 is sufficiently long so that there is no substantial change in length of the spring as the switch arm 11 oscillates and the pressure of the spring on the switch arm is substantially constant.

A stationary contact 19 of the flasher is positioned to be engaged by a cooperating movable contact 20 mounted on the switch arm 11 adjacent the knife-edge connection 16, the flasher being in the "on" position when the contacts are together and "off" when the contacts are separated.

The portion 21 of the switch arm 11 which is on the side of the pivot 12 that is opposite to the knife-edge 16 is somewhat resilient. One end of a hot wire 22 is attached to the free end of arm portion 21, and the other end of the hot wire is attached to a fixed abutment 24, located somewhat above the switch arm 11. In practice, the wire 22 may be formed of the nickel-chrome-manganese-iron alloy resistance wire commonly known as "Nichrome."

The length of the wire 22 is such that at atmospheric temperatures the wire 22 is under tension and exerts a pull on the end portion 21 of the switch arm 11. This deflects the portion 21 of the switch arm somewhat and oscillates the switch arm against the abutment 17. The contacts 19 and 20 are now separated. As the temperature of the wire 22 increases, the wire lengthens somewhat due to expansion, lessening the moment on the switch arm 11 and permitting the spring 14 to oscillate the switch arm in the opposite direction so as to close the contacts 19 and 20.

An electrical lead 25 is connected with the switch arm 11, and the contact 19 is connected directly to a lamp 26 by a conductor 27. The abutment end of the hot wire 22 is connected with the conductor 27 by a conductor 29. The arrangement is such that when the flasher is in normal or starting condition, the wire 22 is cold (i. e. at atmospheric temperature) and the contacts 19 and 20 are separated, the switch arm 11 resting against the abutment 17, and the end portion 21 of the switch arm being deflected upward slightly due to pull of the wire 22.

Upon establishing an electrical circuit to the lead 25, as by manually closing switch 13, the wire 22, which is of relatively high resistance and in series with lamp 26, will be heated by the passage of electric current, although the current will be insufficient to light the lamp 26. As the temperature of the wire 22 increases, it lengthens somewhat and thus decreases the force or moment tending to hold the switch arm 11 against the abutment 17. When the effect of the hot wire pull on switch arm 11 drops below the effect of the biasing spring 14, the spring 14 oscillates the

switch arm with a snap action. This closes the contacts 19 and 20 and establishes a direct connection between the lead 25 and the lamp 26 to light the lamp, the flasher then being in the position indicated in Fig. 1.

Inasmuch as the direct circuit through the contacts 19 and 20 is of very low resistance as compared with the circuit through wire 22, substantially all of the current passing through lamp 26 will pass through the direct circuit and the current passing through hot wire 22 will drop to substantially zero. The wire 22 is of such small diameter that it cools quickly. As it cools, it shortens and increases the force or moment exerted by it on the switch arm 11 until it overpowers the moment caused by spring 14. At this point the contacts 19 and 20 are separated with a snap action and break the direct circuit to the lamp 26, whereupon the cycle will commence again. By varying the specific design of this flasher within the general construction and arrangement above set forth, the time interval of both the "on" and "off" periods of the lamp 26 may be accurately controlled or varied, as well as the time interval required for the entire cycle.

Increasing the air gap between the contacts when in "off" position or increasing the pressure of the spring 14, decreases the number of flashes per minute, the other factors remaining the same, while increasing wire tension increases the number of flashes per minute. An increase of voltage or any other factor that increases the rate at which the wire 22 heats and lengthens tends to increase the number of flashes per minute. For the ordinary signalling lamp a rate of about 80 to 95 flashes per minute is desirable, with the "on" period approximating the "off" period.

A feature of the construction shown diagrammatically in Fig. 1 is that as the wire 22 becomes heated and lengthens, the end portion 21 of the arm straightens and the wire 22 swings toward the pivot 12, thus decreasing the moment which the wire imposes on the switch arm 11. When this moment falls below the opposite acting moment on the switch arm imposed by the spring 14 with the contacts fully opened, the switch arm oscillates to closed position. As the switch arm commences to move away from the axis of the pivots 12 and 15, the moment caused by spring 14 increases rapidly, the pressure being substantially constant and the lever arm rapidly increasing. At the same time, the counteracting moment imposed by the hot wire is relatively constant, the end portion 21 of the switch arm 55 being deflected slightly. Thus, the contacts close with a fast snap action.

After the contacts 19 and 20 have closed, the wire 22 will commence to cool and shorten thus exerting a constantly increasing force on the resilient end portion 21 of the switch arm 11. This force deflects the portion 21 of the arm upwardly, thereby storing energy in springy portion 21 and creating a constantly increasing counteracting moment tending to open the contacts. When this moment exceeds the moment of the spring 14, the contacts will open. As the contacts start to open, the lever arm at which spring 14 acts on the switch arm 11 diminishes rapidly, thereby rapidly diminishing the bias which tends to close the contacts. Thus, the contacts snap open quickly, under the influence of the energy stored in springy portion 21 of the switch arm.

While the counteracting moments are substantially equal in each instance at the instant the movement of the switch arm 11 commences, in

each instance the degree of unbalance very rapidly increases as the contact 20 moves, thereby producing a very rapid make or break of the contacts 19 and 20 without the interplay of any force other than the force of the hot wire 22 and the force of the biasing spring 14.

The flasher previously described may be constructed of a stack or pile of steel plates that have been cadmium plated to prevent rusting. The plates have peripheral edge portions provided with holes for reception of rivets to secure the assembly, the edge portions of the plates collectively forming a frame or housing for the operating portions of the flasher. In describing the plates and the assembly made therefrom, corresponding parts will be designated by the same reference characters used in Fig. 1.

Reference will now be had to Figs. 4 and 5, which show a two-part steel plate composed of parts 30 and 31 which lie in a common plane and meet end-to-end at 33. Metal is stamped out from part 30 as shown to have a centrally located projecting spring 14 which is the biasing spring 14 of Fig. 1. By means of overlapping kerfs 31, 39 and 37, 39 the metallic connection between spring 14 and the outer portion of part 30 is so reduced and arranged as to form (in effect) the pivoted connection 15 (see also Fig. 1).

Metal is similarly stamped out from plate part 31 to form a portion of switch arm 11. By means of overlapping kerfs 32, 34 and 32, 34 the metallic connection between the arm 11 and the outer portion of part 31 is reduced and arranged to form (in effect) the pivoted connection 12 (see also Fig. 1).

The end portion 21 of the switch arm 11, for receiving the hot wire 22, may be tapered from the pivot 12 so as to bend uniformly throughout its length under the pull of wire 22. A rigid strip 35 is secured to the remainder of the switch arm 11 by rivet 36 and provides a rigid arm from the pivot 12 to the knife-edge connection 16. The contact 20 is formed of a strip of silver inlaid on one side of the strip 35 adjacent the knife-edge connection 16 (see also Fig. 6), the inlaid strip also forming one side of a slot receiving the free end of the spring 14 to form the knife-edge connection. The portion 21 of the switch arm 11 is laterally offset somewhat as indicated in Fig. 4 to provide clearance for the hot wires when both the flasher and relay are combined in a single structure, as in Fig. 3.

Referring now to Fig. 3, the entire stack of plates and parts forming the flasher and relay are shown in exploded relation. All of these plates are provided with registering marginal holes used to facilitate assembly of the flasher and to receive rivets or other fasteners for securing the assembled plates.

A plus or line terminal plate 41, which is positioned adjacent to the bottom of the stack of plates, is provided with a terminal 42 for receiving the wire 25 of the Fig. 1 and is also provided with a bridge portion forming the abutment 17 that prevents the knife-edge connection 16 from passing below the axis of the pivots 12 and 15. The underside of the line terminal plate 41 is covered by a cover plate 44 to inclose the bottom of the flasher unit. The inside of the cover plate may be insulated from plate 41 by a coating of lacquer.

The next plate of the series comprises the two-part plate 30, 31 of Fig. 4, this plate including the switch arm 11 and spring 14. Above this plate is provided a spacer plate 45 which may be coated

with lacquer to insulate it from the plate next above. This plate determines the air gap or spacing between the contacts 19 and 20 when the switch arm 11 is against the abutment 17. Above the spacer plate 45, a plate 46 is provided which has a bridge portion forming the contact 19. A small silver contact button may be provided on the bridge portion of the plate if desired.

The next succeeding plate 47 is formed in two U-shaped parts as indicated in Fig. 3 for convenience of assembly of the flasher. This plate is provided at one end with a knurled portion forming the abutment 24 for receiving an end of the hot wire 22 extending to the switch arm 11. For convenience of attachment of the wire 22 to the portion 21 of the switch arm, it is desirable to use a single wire having its mid portion looped about the portion 21 of the switch arm and the two ends attached to the abutment 24, the two branches of the wires functioning together as a single length of hot wire.

The next succeeding four plates, including the spacer plates 49 and 51 and which are similar to the spacer plate 45, the relay terminal plate 50, and the two-part switch arm and spring plate 52, 54 need be inserted only when it is desired to have a relay incorporated in the flasher unit. The nature and function of these four plates will be explained hereinafter. If these four plates are omitted, the load terminal plate 43, which is identical to plate 41 but in inverted position, may be mounted directly on plate 47, the terminal 48 of the plate 43 receiving the wire leading to the lamp or lamps 26 to be controlled. A second cover plate 44, which is lacquered on the inside, covers the top of plate 43.

With the relay plates omitted the current passing into the line terminal plate 41 is conducted into plate portion 31 and switch arm 11, from whence the current passes upwardly through the wire 22 and to the load terminal plate 43. When the contacts 19 and 20 are closed by upward movement of the switch arm 11, the current passes directly from the switch arm 11 to the plate 46, the plate 47 and into the plate 43 in order to light the lamp.

When the relay is incorporated in the flasher, it may be connected into a circuit for indicating to a person driving an automobile that the signal lamps are in operation. In a form shown of this invention, the flasher unit is designed to flash a lamp at both the front and rear of the car to indicate a right or left turn. The relay is provided to control a monitor circuit lighting a pilot light 55 (Fig. 2) on the instrument panel of the automobile.

The physical structure of the relay switch is generally similar to that of the flasher switch hereinbefore described. The switch arm and spring plate portions 52 and 54 of the relay are identical respectively with plate portions 31 and 30 of the flasher but in inverted position. Below these plates, the spacer plate 51, which is insulated by lacquer on its top surface, serves to space the switch arm 53 from the relay terminal plate 50, which is provided with a bridge portion forming a contact 56 for the switch arm of the relay. A spacer plate 49, which is insulated by lacquer on its top surface, separates the plate 50 from the abutment plate 47.

A hot wire 57 serves to operate the relay, this wire being similarly arranged to the wire 22 but of much lower electrical resistance. In the flasher of the present invention as applied to 6 volt automobile electrical system, the hot wire 22

may have an electrical resistance of about 2 ohms while the hot wire 57 may have a resistance of about one half ohm or less. The hot wire 57 is in series with hot wire 22, the latter wire being cyclically shunted by the closing of contacts 19, 20. When the signal lamps are lighted, the lamp current passes through wire 57, but is shunted around wire 22.

A front signal lamp is in parallel with a rear signal lamp and, therefore, when both are operating, the current through hot wire 57 is twice as great as when one of these lamps has burned out. The action of the relay is such that when both the front and rear signal lamps of the automobile are operating, the wire 57 is heated sufficiently to enable the relay switch arm 53 to engage the contact 56 of the relay terminal plate 50 to complete the circuit to the pilot light 55 (Fig. 2) while, if one or both of the lamps at the front and rear of the car are not operating, there will be insufficient current passing through the wire 57 to cause it to heat and expand sufficiently to complete the circuit to the light 55.

Since the wire 57 is sufficiently heavy it will not, once it has been heated, cool enough during the time that the direct circuit to the lamps is interrupted by the flasher to cause the relay circuit to the pilot light to be interrupted. However, when the direct circuit to the signal lamps is interrupted, the relatively large resistance of wire 22 is introduced into the circuit and this extinguishes the pilot lamp 55 the same as the signal lamps 26. Thus, the pilot lamp flashes when both signal lamps are flashing.

The construction of the flasher unit is particularly adapted for ease of assembly. The flasher is assembled on studs, not shown, the plates being individually stacked from bottom to top on studs passed through holes 59, 59 and 60, 60 in the bottom cover and the corresponding holes in the rest of the plates. By this arrangement, the switch arm plate part 31 may be inserted first and the spring plate part 30 inserted later so as to engage the end of spring 14 with the switch arm 11 to form the knife-edge connection 16.

The right end part of the abutment plate 47 is slipped in after the remainder of the plates have been assembled, this part of the plate 47 having a pair of open holes or slots to permit later insertion onto the studs.

After assembly of the flasher, rivets 61 (Fig. 2) may be inserted through the marginal holes to hold the entire stack of plates in assembled relation, the rivets being temporarily omitted from the pair of holes at the right end of the flasher. The rivets are insulated throughout their length to prevent electrical contact with the plates.

Small wedges, not shown, may be introduced between the abutment end of abutment plate 47 and the next adjacent plates 46 and 49 to space these plates slightly until the wires 22 and 57 have been properly tensioned. After tensioning the wires to the predetermined tension for the flasher characteristics desired, the wedges may be removed permitting the plates to come together and rigidly clamp the wires. The remaining rivets are then added to aid in holding the entire assembly.

The flasher of the present invention has a rigid case formed of the steel plates, which is not easily distorted. The moving parts are held to a minimum and there are no fragile parts thus assuring dependability of operation and making the device resistant to physical shock and otherwise very durable.

The pivots 12 and 15 formed by the overlapping kerfs are easily formed and are durable. Also, the pivot 12 may deflect or raise somewhat under pull of the wire 22, forming in effect a somewhat resilient pivot and permitting greater tolerance in adjusting the tension of the wire.

The flasher may be incorporated in the circuit indicated in Fig. 2. In this circuit, the automobile battery 62 or other source of power is connected with the line terminal 42 of the flasher. A selector switch 64 of a well known type, which is customarily mounted on the steering column, is connected with the load terminal 48. The selector switch 64 may be operated to illuminate either the right-hand or the left-hand pairs of lamps 26 to indicate either a right turn or a left turn, it being understood that one lamp of each pair is on the front of the car while the other lamp of the same pair is on the rear of the car. The relay terminal plate 50 is connected with the pilot light 55 to indicate operation of both lights 26 of the selected pair.

The flasher and relay of the present invention does not include any electro-magnetic device, and hence is equally suitable for use with either direct or alternating current.

I claim:

1. The method of obtaining rapid acceleration for the opening and closing of the contacts of a flasher for interrupting an electrical circuit at frequent regular intervals, the flasher having a contact arm mounted for pivotal movement and the arm being continuously biased towards closed position by a moment which varies between a maximum at closed position of the contacts and a minimum at fully open position, said method comprising: applying a counteracting moment to the arm and varying the counteracting moment to alternate it between values greater than the maximum and less than the minimum of the biasing moment, and storing the energy of the counteracting moment without any relative movement of the contacts until such time as the counteracting moment overcomes the biasing moment.

2. The method of obtaining rapid acceleration for the opening and closing of the contacts of a flasher for interrupting an electrical circuit at frequent regular intervals, the flasher having a contact arm mounted for pivotal movement and the arm being continuously biased towards closed position by a moment which varies between a maximum at closed position of the contacts and a minimum at fully open position, said method comprising: applying a counteracting moment to the arm while the contact arm is stationary, varying the counteracting moment to alternate it between values greater than the maximum and less than the minimum of the biasing moment, and restraining the contacts from any relative movement until the instant of separation of the contacts.

3. The method of obtaining rapid acceleration for the opening and closing of the contacts of a flasher of the type in which a pivoted contact arm is continuously biased towards closed position and is periodically held in open position by an opposing moment of intermittently varying magnitude, said method comprising: arranging the opening and closing moments on the contact arm such that, upon both opening and closing movement of the contact arm, the difference between the moment causing the motion and the moment resisting the motion is rapidly increased as the initial movement of the contact arm takes

place, the contacts being restrained from any relative movement until the instant of their separation.

4. The method of obtaining rapid acceleration for the opening and closing of the contacts of a flasher of the type in which a pivoted contact arm is continuously biased towards one position and is periodically held in another position by an opposing moment of intermittently varying magnitude, said method comprising: arranging the opening and closing moments on the contact arm such that, upon both opening and closing movement of the contact arm, the difference between the moment causing the motion and the moment resisting the motion is rapidly increased as movement of the contact arm takes place, the contacts being restrained from any relative movement until the instant of their separation.

5. The method of obtaining rapid acceleration for the opening and closing of the contacts of a flasher for interrupting an electrical circuit at frequent regular intervals, the flasher having a contact arm mounted for pivotal movement and the arm being continuously biased towards closed position by a single force causing a moment on the arm which varies between a maximum at closed position of the contacts and a minimum at fully open position, said method comprising: applying a single force causing a counteracting moment alternately varying between an amount greater than the maximum and less than the minimum of the first moment, the contacts being restrained from any relative movement until the instant of their separation.

6. The method of obtaining rapid acceleration for the opening and closing of the contacts of a flasher for interrupting an electrical circuit at frequent regular intervals, the flasher having a contact arm mounted for pivotal movement between open and closed position and the arm being continuously biased towards one position by a moment varying between a maximum at the one position and a minimum at the other position of the arm, said method comprising: applying a counteracting moment to the arm and varying the counteracting moment to alternate it between an amount greater than the maximum and less than the minimum of the first moment, and storing the energy of the counteracting moment without any relative movement of the contacts until such time as the counteracting moment overcomes the biasing moment.

7. A flasher of the hot-wire type, comprising: a switch arm pivotally mounted between its ends, one end portion being substantially rigid and the other end portion being resilient, an electrical contact in the path of movement of the switch arm, a spring biasing the switch arm at constantly increasing moment as it approaches the contact, and a tensioned wire intermittently heated by passage of electric current and having one end anchored and the other end attached to the resilient end portion of the switch arm for supplying a moment acting counter to the moment of the spring and alternately less than the minimum and greater than the maximum moment caused by the spring.

8. A flasher of the hot-wire type as claimed in claim 7, in which the wire is continually in an electric circuit through the flasher and the current passing through the wire is varied by periodically establishing a circuit in shunt of the wire, whereby the wire is alternately heated and permitted to cool.

9. A flasher, comprising: a switch arm pivotal-

ly mounted between its ends, one end portion being substantially rigid and the other end portion being resilient, an electrical contact in the path of movement of the switch arm, a spring biasing the switch arm at constantly increasing moment as it approaches the contact, and a tensioned wire and means to intermittently heat the same, the wire having one end anchored and the other end attached to the resilient end portion of the switch arm for supplying a moment acting counter to the moment of the spring and alternately less than the minimum and greater than the maximum moment caused by the spring.

10. In a flasher for interrupting an electrical circuit at frequent regular intervals, a stack of superimposed plates having substantially continuous similar peripheries forming a housing, one of the plates being resilient and having an integral portion within the periphery of the plates forming a switch arm substantially coplanar with the plate and pivotally attached to the periphery thereof for pivotal movement in a plane perpendicular to the plate.

11. In a flasher for interrupting an electrical circuit at frequent regular intervals, a stack of superimposed plates having substantially continuous similar peripheries forming a housing, one of the plates being resilient and having an integral portion within the periphery of the plate forming a switch arm substantially coplanar with the plate and pivotally attached to the periphery thereof for pivotal movement in a plane perpendicular to the plate, the pivoted mounting being formed by a pair of overlapping offset kerfs in the plate at each side of the switch arm.

12. In a flasher for interrupting an electrical circuit at frequent regular intervals, a stack of superimposed plates having substantially continuous similar peripheries forming a housing, a switch arm mounted for pivotal movement within the housing, and one of the plates being resilient and having an integral portion within the periphery of the plate forming a switch-arm-biasing spring pivotally mounted on the periphery for pivotal movement in a plane perpendicular to the plate, the pivotal mounting being formed by a pair of overlapping offset kerfs in the plate at each side of the spring.

13. In a flasher of the hot-wire type, a stack of superimposed plates having substantially continuous similar peripheries forming a housing, one of the plates forming a switch arm and a switch arm biasing spring both substantially coplanar with the plate and pivotally mounted on the periphery thereof for pivotal movement in a plane perpendicular to the plate.

14. A unitary organization constituting a flasher for periodically interrupting a flasher circuit combined with a relay responsive to current flowing through the flasher circuit for controlling a monitor circuit showing operation of the flasher circuit, said flasher and relay comprising a stack of superimposed plates having substantially continuous similar peripheries forming a housing, one of the plates including a pivotally-mounted switch arm biased to closed position to complete a low resistance flasher circuit through the flasher, a hot-wire continuously in the flasher circuit for moving the switch arm to interrupt the low resistance flasher circuit, and another of the plates including a relay switch arm biased to closed position to energize the monitor circuit, and a second hot-wire in series with the flasher circuit and responsive to drop in current through the flasher circuit to a predetermined minimum

to move the relay switch arm against its bias and thereby interrupt the monitor circuit.

15. A combined flasher and relay as claimed in claim 14, in which the plate including the flasher switch arm and the plate including the relay switch arm are similar.

16. A flasher comprising: a stationary contact and a movable contact; a pair of spaced pivots; shiftable means extending operatively from one pivot to the other, the movable contact being carried by said shiftable means and said shiftable means being movable towards and away from said stationary contact and continuously biased in one direction; resilient energy-storing means located outside of the space between parallel planes passing through said pivots at right angles to a line connecting the pivots, said energy-storing means being operatively connected to said shiftable means; and hot-wire control means connected to the energy-storing means and operative to intermittently stress the energy-storing means to store energy therein, the stored energy opposing the bias of the shiftable means, the

5

10

20

stored energy periodically being of such magnitude as to overcome the bias of the shiftable means so as to actuate said shiftable means, thereby releasing a portion of the stored energy, the remaining stored energy being additionally released over an interval of time by action of the control means decreasing the stress imposed upon the energy-storing means.
